(57) **CLAIM**

The ornamental design for a rod strap hook, as shown and described.

DESCRIPTION

FIG. 1 is a front and right side perspective view of a rod strap hook showing my new design;

FIG. 2 is a front and right side perspective view thereof with an end of a strap wrapped upon it;

FIG. 3 is a top plan view thereof, shown reduced in scale;

FIG. 4 is a rear elevation view thereof;

FIG. 5 is a front elevation view thereof;

FIG. 6 is a right side elevation view thereof; and,

FIG. 7 is a bottom plan view thereof.

The broken lines showing a strap wrapped onto the rod strap hook in FIG. 2 depict an environment of use and form no part of the claim.
